UNITED STATES PATENT OFFICE.

LEWIS C. BROOKS, OF MILWAUKEE, WISCONSIN, ASSIGNOR TO THE NATIONAL PAPER CAN COMPANY, OF MILWAUKEE, WISCONSIN, A CORPORATION OF WISCONSIN.

CONTAINER CLOSURE.

Application filed November 25, 1921. Serial No. 517,508.

To all whom it may concern:

Be it known that I, LEWIS C. BROOKS, a citizen of the United States, residing at Milwaukee, county of Milwaukee, and State of Wisconsin, have invented a new and useful Improvement in Container Closures, of which the following is a full, clear, and exact description.

The present invention relates to container closures. The object of the invention is to produce a simple and cheap closure which may be readily opened by the consumer. The closure is completed by means of an adhesive strip or tape which seals the joint between the lid and the container body.

In the illustrated embodiment of the invention,—

Figure 1 is a side elevation, partly in section, and

Figure 2 is a plan view showing the adhesive strip partly removed.

Referring to the preferred form of the invention illustrated in the drawings, the container has a body portion 1 and a lid 2. While the lid may be applied to the container body in different ways, in the drawings the lid is illustrated as a snap closure fitting against an internal annular seat 3. This annular seat 3 is formed by bending the material of the body downwardly and inwardly and back upon itself to form the seat 3 shown in the drawings. This frictionally holds the closure 2 when it is snapped in position. The joint around the edge of the closure 2 is sealed by means of an adhesive

strip or tape 4. This strip may be made of any suitable material impregnated or coated with a suitable adhesive. The usual cloth tape impregnated with a rubber solution is found to be satisfactory, particularly for use with cans made of paper impregnated with paraffine. The rubberized tape readily sticks to the paraffine surface. The tape not only assists in holding the lid 2 in place, but forms an air tight seal over the joint between the lid and the can body.

It is to be understood that the present invention is not limited to its illustrated embodiment, but may be otherwise embodied within the scope of the following claims.

I claim:

1. A container having a paraffine impregnated paper body and a paraffine impregnated closure, and a tape having an adhesive substance thereon which will adhere to the paraffined surfaces applied over the joint between the container body and closure, substantially as described.

2. A container having a paraffine impregnated paper body formed with an internal annular seat at its mouth, a paraffine impregnated snap closure disk seating thereon, and a cloth tape impregnated with a rubber adhesive applied over the joint between the container body and the disk closure, substantially as described.

In testimony whereof I have hereunto set my hand.

LEWIS C. BROOKS.
